UNITED STATES PATENT OFFICE.

HENRY G. THOMPSON, OF NEW HAVEN, CONNECTICUT, ASSIGNOR TO THE NEW HAVEN NOVELTY MACHINE COMPANY, OF SAME PLACE.

DESIGN FOR A PIPE-CO尤PLING.

SPECIFICATION forming part of Design No. 33,307, dated October 2, 1900.

Application filed August 17, 1900. Serial No. 27,216. Term of patent 14 years.

To all whom it may concern:

Be it known that I, HENRY G. THOMPSON, a citizen of the United States, residing at New Haven, county of New Haven, and State of Connecticut, have invented and produced a new, useful, and original Design for a Pipe-Coupling, of which the following is a specification, reference being had to the accompanying drawings, forming a part thereof.

10 Figure 1 is a side elevation, partly broken out, of a pipe-coupling, illustrating my design; and Fig. 2 is a left-hand end view thereof.

15 The leading feature of my design for a pipe-coupling consists in an exteriorly-polygonal tubular body having an internal spirally-threaded bore, a circular peripherally-grooved head at one end of the body, and a tubular externally-tapering projection extended centrally from the outer face of the head in axial 20 alinement with the body.

25 Referring to the drawings illustrating my design, the tubular body m is externally polyg-

onal, as at m' , and provided with an internal spiral thread m^2 , one end of the body having a circular head or flange m^3 , peripherally grooved, as at m^4 , a tubular externally-tapering projection m^5 extending from the outer face of the head in axial alinement with the body, the bores of body and projection communicating and being of different diameters, 30 as shown.

Having fully described my design, what I claim as new, and desire to secure by Letters Patent, is—

35 The design for a pipe-coupling, substantially as herein shown and described.

In testimony whereof I have signed my name to this specification in the presence of two subscribing witnesses.

HENRY G. THOMPSON.

Witnesses:

H. GRANT THOMPSON,
GEORGE E. HAIGHT.
